Robert Schulze

UNITED STATES PATENT OFFICE.

ROBERT SCHULZE, OF COVINGTON, KENTUCKY.

CENTRIFUGAL BOLT.

SPECIFICATION forming part of Letters Patent No. 423,635, dated March 18, 1890.

Application filed August 16, 1889. Serial No. 320,965. (No model.)

To all whom it may concern:

Be it known that I, ROBERT SCHULZE, a citizen of the United States, and a resident of Covington, in the county of Kenton and State 5 of Kentucky, have invented certain new and useful Improvements in Centrifugal Bolts, of which the following is a specification.

My invention relates to that class of milling-machines known as "centrifugal bolts."

10 The objects and features of my invention will fully appear from the following description of the accompanying drawings, in which like parts are indicated by similar reference-letters wherever they occur throughout the 15 various views, and in which—

Figure 1 is a view in longitudinal section of a bolt embodying my improvements. Some of the parts are shown in elevation, and some parts are broken out to expose the parts back 20 of them. Fig. 2 is a transverse vertical section taken through line $x-x$ of Fig. 1. Fig. 3 is a fragmentary section of the appliances for holding the ends of the bolting-cloth and stretching the same. Fig. 4 is a fragmentary 25 view, in elevation, of the rear wall of the chest. Fig. 5 is a similar view of that portion of the chest to which the air-inlet valve is secured.

The outer casing A may be of the usual form, the lower portion being inclined, as usual, to 30 discharge into the ordinary conveyer. (Not shown.)

Across each end of the chest is a bridge-tree A' to support the bearings b, in which the flier-shaft B is supported.

35 Upon the flier-shaft, near each end of the chest, is secured a wheel C. These wheels have outwardly-projecting inclined bracket-arms c, to which are secured the blades C'. The arms c of the opposite wheels C are so 40 arranged that the blades when secured in place are spirally inclined, as shown, so as to carry the stock under treatment from the head toward the tail of the machine.

The flier composed of the shaft B, its wheels 45 C c, and the blades C' revolves within a bolting-chamber composed of the sheet-metal segmental sheet D and the bolting-cloth E. The sheet-metal shell, which extends from end to end of the chest, sheathes part of the back 50 and top of the chest and curves around at the bottom in the arc of about one-quarter of a circle, its lower end being secured upon the

top edge of a longitudinal board or partition F, which extends from the head to the tail of the chest.

To each end of the machine on the inside is secured the pieces G, the outlines of which conform to the lines formed by the outlines of the metal shell D, bolting-cloth E, and the two longitudinal boards or partitions H and I. 55 The angular partitions formed by the boards H and I extend from end to end of the chest A, and their opposite ends are secured upon the angular edges of the pieces G. That portion of heads G around which the bolting-cloth E passes is rabbeted at g to receive segmental cleats which press and hold the bolting-cloth in place, and they are also provided with V-shaped grooves at g' for the purpose of receiving the beveled edges of the segments J for the purpose of stretching the bolting-cloth from end to end, which is accomplished as follows:

K K' are segments held upon each end of the bolting-chest by buttons k. The segments J J are adjustably secured to the segments K by set-screws and thumb-nuts j. The bolting-cloth E has at each end loops formed by turning over the edges. Small segmental fastening-cleats, which may be of 80 wire, either square or round in cross-section, are then passed through these loops, forced into the rabbets g, formed in end pieces G, and held in place by the segments K and buttons k. The segments J are then forced in- 85 ward to give the cloth the requisite tension and secured in place by the thumb-nuts and set-screws j. The longitudinal edges of the bolting-cloth are also formed into loops and are held in the bars L L'. Each of these bars 90 is longitudinally perforated and slotted from the edge into the perforation. The opposite longitudinal edge of the bolting-cloth is passed through these slots into the enlarged perforations, and wires passed through the 95 loops of the cloth to fasten its edges to these bars L L'. The lower one of these bars L' is held rigidly in place against the longitudinal board or partition F by a bar F', upon the upper edge of which the bar L' rests and the 100 buttons f, which are secured upon the bar F by screws. The opposite bar L, with the edge of the bolting-cloth secured in it, rests upon the horizontal partition H, and is held in place

by eccentric collars M, which are mounted upon stud-bolts m, which pass through the vertical board M' and washers m'. The collars M have levers or handles m², by which they are turned, and also pins m³, which strike against pins m⁴, projecting from the washers m', and stop the further rotation of the eccentric collars when the lowest point of its cam-surface is just above the bar L. The bolting-cloth is tightened by forcing the bar L inward in the direction of the partition M', then clamping it down by means of the eccentrics M, which are held from turning by the thumb-nuts m⁵ after the bar L has been clamped in the proper position.

N and N' are strips extending longitudinally of the chest, to the lower edges of which is secured the segmental plate N², which is concentric with the flier, the trips N N and segmental plate N² forming a triangular partition extending from end to end of the chest. In the upper rear corner of the chest are two strips or baffle-plates N³ N⁴, which also extend from end to end of the chest.

O are blades, of which there may be any desired number, arranged at regular distances apart. These are secured upon rock-shafts o, which extend out from the back of the chest and are provided with crank-arms o', the lower ends of which are connected to a bar o², whereby the cranks and rock-shafts are simultaneously moved to give the blades O any desired inclination, either to retard or advance the stock under treatment. One of the arms o' or the bar o² is provided with a set-screw o³, which enters one of several perforations in the back wall of the chest to retain the blades O in the position desired.

P is the spout through which the stock is fed to the machine; Q, the discharge-spout for the bran and light material, which is blown to the top of the chest by the fliers, and R is the discharge-spout for the heavy stock, which is too coarse to pass through the bolting-cloth.

S is a valve at the head of the machine to regulate the amount of air admitted to the chest, and G', Fig. 1, is a light metal hoop or band of the same shape in edge elevation as the part of the ends G, around which the bolting-cloth is stretched. The purpose of this band is to hold the center of the bolting-cloth out so that it will not be struck by the edges of the flier-blades when the machine is in operation.

The operation of my machine is as follows: The stock is fed to the machine through the feed-spout P, (within or above which any suitable feed appliances may be located,) and being caught by the flier-blades C' is thrown by centrifugal force outward. A current of air induced by the blades enters through the valve S and carries the lighter portions up toward the top of the chest and out through the spout Q at the tail of the bolt. The heavier parts of the stock are deflected by the baffle-plates N N' N² N³ N⁴ and the board I and again brought under the action of the flier-blades C' and

thrown outward with considerable force against bolting-cloth, through which the separated stock passes and is carried down to the conveyer-boxes. The heavier stuff which is rejected by the bolting-cloth is carried to the tail of the machine and discharged through the tailing-spout R. If it is found that the dust discharged through spout Q contains some flour or stock that should pass through the bolting-cloth, the supply of air admitted through the valve S is reduced by partially closing the valve. If the stock is being carried too rapidly to the tail of the machine, it is retarded by turning the blade O from the perpendicular, as indicated in dotted line, Fig. 1. The movement of the stock is accelerated by turning the blades in the opposite direction. The same result will also be accomplished by changing the incline of the blades C', which may be accomplished by loosening the set-screw which holds one of the wheels C upon the shaft B and turning it partially around. The bolting-cloth need not be stretched so tight as on the ordinary cylindrical reel, as it is desirable that it should vibrate by the force of the stock thrown against it. This vibratory motion keeps the meshes free and obviates the necessity of brushing or otherwise cleaning it.

It will be seen that the machine requires much less bolting-cloth than those in common use. It has few journals and bearings to require attention or cause friction, and therefore requires less power to run it, and I have found that a small machine made as above described will finish more stock than a much larger one made after the most approved patterns now in use.

The plates or partitions N N' N² N³ N⁴ serve in separating the stock; but the machine would be effective without either or all of them, but the bolting-cloth would be subjected to heavier duty.

It is obvious that other well-known fliers may be employed with my reel, but not with the same advantage.

I claim—

1. In a centrifugal bolt, the combination of the chest A, the bolting-concave consisting of the heads G, secured to each end of the chest, the sheet-metal segmental shell D, and the bolting-cloth E, the partition F, to support the end of shell D, and the fliers mounted to revolve within said concave and having spirally-inclined blades C', substantially as hereinbefore set forth.

2. The combination, substantially as specified, of the bolting-chest, the heads G, secured to the ends thereof, the sheet-metal shell D, bent around the rear portion of said heads, the plates H I, extending lengthwise of the chest and secured upon said heads, the longitudinal partition F, upon which the lower edge of the shell D rests, the bolting-cloth stretched around said heads from the edge of shell D to the plates H, and means, such as shown, to stretch and hold the bolting-cloth

in place, the hoop-segment G', to support the bolting-cloth at its center, and the flier having spirally-inclined blades arranged to revolve within the reel formed by the sheet-metal shell and bolting-cloth, for the purpose set forth.

3. The combination of the chest A, having air-valve S at the head and dust-discharge leading from the top at tail end, the heads G, 10 the triangular partition formed by the plates N N' N², the sheet-metal shell D and bolting-cloth E, the partitions H, I, and F, means for holding and stretching the bolting-cloth, the central support G', for the bolting-cloth, the 15 flier-shaft B, wheels C, having inclined arms c, and the spirally-arranged flier-blades C', constructed and arranged to operate substantially as specified.

4. In a centrifugal bolt, the combination of 20 the chest, the reel consisting of the heads G,

shell D, bolting-cloth E, and plates H I, secured on said heads, the partitions N N' N² N³ N⁴, arranged in the rear upper portion of said reel, and the flier having spirally-inclined blades C', arranged to revolve within 25 said reel, substantially as shown and described.

5. In a centrifugal bolt, the combination of the chest, the reel-heads G, having grooves and rabbets, the partitions H M', the bolting-cloth E, the bars L L', to which the edges of the bolting-cloth are secured, the segments J K, buttons k, and thumb-nuts j, for stretching the cloth endwise the bar L, and eccentric M, for stretching it around the heads, 30 35 and hoop G', substantially as specified.

ROBERT SCHULZE.
